UNITED STATES PATENT OFFICE.

PETER SHANNON, OF CHICAGO, ILLINOIS.

HYDRAULIC STREET-CLEANING APPARATUS.

SPECIFICATION forming part of Letters Patent No. 726,580, dated April 28, 1903.

Application filed May 12, 1902. Serial No. 106,856. (No model.)

To all whom it may concern:

Be it known that I, PETER SHANNON, a citizen of the United States of America, and a resident of Chicago, in the county of Cook and State of Illinois, have invented certain new and useful Improvements in Hydraulic Street-Cleaning Apparatus, of which the following is a specification.

The present invention relates to a system of cleaning city streets by the forcible discharge of a stream of water over the surface of the same, and has for its primary object to provide a simple and efficient arrangement of apparatus in which the lead of hose employed in the operation of washing or flushing the street is automatically unwound with the progress of the operation of washing a predetermined length of the street and subsequently rewound with a completion of the operation of washing such length of street ready to begin the washing or flushing operation upon the next length of street and in connection with such mode of operation to effect a discharge of water through the lead of hose with the required force to attain a rapid and effective cleaning of the street.

A secondary object of the present invention is to provide means whereby the hose can be maintained in a condition filled with water during the operation of winding the same upon its carrying-reel in order that the flow of water will not be interrupted in a subsequent use of the hose during the street-washing operation and while the hose is wholly or partly wound upon such carrying-reel, all as will hereinafter more fully appear and be more particularly pointed out in the claims.

I attain such objects by the construction and arrangement of parts illustrated in the accompanying drawings, in which—

Figure 1 is a side elevation of the reel and truck of the present invention; Fig. 2, a plan view of the same; Fig. 3, a rear end elevation of the same; Fig. 4, a side elevation of a portable auxiliary pumping-engine for use in connection with the present apparatus; Fig. 5, a fragmentary sectional plan view of the same at line x x , Fig. 4; Fig. 6, a diagrammatic view illustrating the electromagnetic controlling mechanism for the throttle-valve of the auxiliary pumping-engine; Fig. 7, an enlarged fragmentary sectional eleva-

tion of the detachable connection between the hose and the auxiliary pumping-engine and illustrating the electric mains by means of which such pumping-engine is governed; Fig. 8, a similar view of the connection between the carrying-reel and the hose; Fig. 9, a detail cross-section at line x' x' , Fig. 8; Fig. 10, a detail plan view of the automatic guide mechanism for the hose in the reeling and unreeling of the same; Fig. 11, a transverse section of the same at line x^2 x^2 , Fig. 10; Fig. 12, an enlarged detail transverse section on line x^3 x^3 , illustrating the auxiliary governing mechanism of the guide mechanism aforesaid.

Similar numerals of reference indicate like parts in the several views.

Referring to the drawings, 1 represents a truck of any usual and approved construction, provided with the usual wheels and steering-gear, as usual in hose-trucks and the like.

2 is a hose-reel journaled by means of a tubular axle 3 in the journal-boxes 1' on the main frame 1 and provided with the usual end heads 4. In the present invention such journal connections between the ends of the tubular axle and the respective journal-boxes are made water-tight by any usual and well-known means which will permit of a turning movement of the tubular axle in the journal-boxes.

5 represents duplicate flexible hose-pipes connected to the outer ends of the respective journal-boxes 1', with their bores in communication with the bore of the tubular axle 3 and adapted to receive water therefrom.

6 represents discharge-nozzles on the free ends of the duplicate hose-pipes 5 aforesaid and adapted to afford means whereby the workmen are enabled to handle the discharge ends of such hose-pipes and direct the issuing streams of water to different portions of the street-surface in the washing or flushing of the same.

7 is a comparatively long lead of hose, one end of which is adapted for attachment to the source of water-supply, as hereinafter more fully set forth, while the other end is attached to a lateral neck 3' of the tubular axle 3, the arrangement being such that the said lead of hose can be wound around said axle and con-

fined in such position by the end heads of the hose-reel 2, and the lead of hose so held is adapted to be unwound in accordance as the hose-carrying truck moves away from the 5 source of water-supply.

8 represents valves or cocks of any suitable form arranged in the nozzles 6 and adapted to shut off the discharge of water therefrom. 9 represents similar valves at the normally 10 free end of the lead of hose 7 and which are adapted to shut off the discharge of water therefrom. The arrangement and purpose of the aforesaid valves 8 and 9 are to confine a filling of water within the hose lead 7, so 15 that the same will maintain a cylindrical form when wound upon its reel, and thus permit of water being forced through such hose while still in a reeled or partly-reeled condition in the progress of the operation of washing the street.

With the present system of cleaning streets the ordinary city-main pressure does not afford a discharge of water forcible enough to effect a rapid and efficient street-cleaning operation with the present type of apparatus 25 and the long lead of hose employed therewith. Accordingly the present apparatus includes an auxiliary pumping-engine as a tender to the hose-truck heretofore described 30 and which truck will be carried from place to place along with the hose-truck to be left at a water-plug or other source of water-supply from which it is adapted to pump the water 35 from such source of supply and discharge the same through the heretofore-described hose-reel and its discharge-nozzles 6 to effect the necessary washing operation upon a section of street or roadway.

In the particular apparatus shown in Figs. 40 4 and 5 of the drawings as illustrative of such auxiliary pumping-engine, 10 is a suitable motor-engine driven in any usual manner from a suitable source of power-supply 45 and which will usually be a steam-generator carried by the wheeled pump-truck 11. 12 is the throttle-valve of such engine, provided with an operating-lever 13, which in turn is connected to the armature 14 of an operating electromagnet or selenoid 15 for a purpose 50 hereinafter set forth. 16 is a fluid-pump of any usual and suitable construction, carried by the truck 11 and operated by the motor-engine 10. 17 is the water-inlet trunk for said pump 16, adapted for connection by a 55 suitable hose with the water-plug or other source of water-supply. 18 is the water-outlet pipe from said pump, adapted for attachment to the lead of hose 7 of the hose-reel heretofore described.

60 The convenient control of motor-engine 10 by the operator upon the main hose reel or truck is attained in the present invention by a construction as follows: 19 is an electrical controller in which may be arranged a series 65 of electric batteries affording the required electric power. Such controller is of any usual form and construction and is provided

with an adjustable handle or lever 20, by means of which a current of any desired strength can be sent along the circuit of the 70 present construction. 21 22 are the circuit-wires, connected, as usual, to the said controller. Such wires extend to the pair of brushes 23 24 in contact with the insulated rings 25 26, which are arranged concentric 75 with the hollow axle 3 of the hose-reel 2, as illustrated in Fig. 8. 27 is a cable containing extensions of the circuit-wires 21 and 22 in insulated relation, and which extensions are connected to the insulated rings 25 and 26. 80 Such cable is arranged within the bore of the lateral neck 3' of the same, and its wires are connected to the insulated binding-posts 28 and 29, arranged at the periphery of such lateral neck. 30 is a similar cable arranged 85 within the bore of the lead of hose 7, the wires of which at one end are adapted for attachment in a detachable manner to the binding-posts 28 and 29 aforesaid, while the other ends of the wires or conductors are 90 adapted for attachment in like manner to the binding-posts 31 and 32 of a coupling-head 33, by which such end of the lead of hose 7 is connected to the pump 16 of the auxiliary pumping-engine. From the binding-posts 31 and 32 conductor-wires extend to the operating-electromagnet 15, heretofore described, by which the throttle-valve 13 of the motor-engine 10 is governed and controlled. Such connection between the last-mentioned conductor-wires may be effected by the usual plug 34 or other usual circuit-making provision.

With the arrangement described the operator upon the hose truck or reel is enabled to 105 conveniently govern the action of the auxiliary pumping-engine to suit the particular requirements met with in the progress of the work.

In order to lay the lead of hose 7 upon the 110 reel 2 in a uniform manner in the winding-up or reeling operation, any usual and suitable automatic guiding mechanism may be employed. In Figs. 1, 2, 3, 10, 11, and 12 I illustrate an automatic mechanism for such 115 purpose, and in which 35 is a counter-shaft receiving positive rotation by gearing connection or other usual means from one of the driving-wheels of truck 1 and carrying a driving-pulley 36, as shown in Fig. 1. 37 is an intermediate shaft journaled on the truck-frame and carrying a pulley 38, which is connected by a belt 39 with the pulley 36 aforesaid. 40 is a tightener-pulley having link-and-lever connections, as shown in Fig. 1, 120 with an operating-lever 41 adjacent to the operator's seat or station on the main truck, the arrangement being such that the operator is enabled by means of such tightener to either tighten the belt, so that both pulleys 125 will revolve in unison, or to loosen such belt, so that the intermediate pulley 38 will have no revolution on account of the slippage of the belt thereon. 42 is a belt connecting a

pulley on the intermediate shaft 37 with a similar pulley on the hose-reel 2 and adapted to impart rotation thereto in unison with the rotation of such shaft 37, as before described. 43 is a traversing carriage, arranged to move back and forth across the rear end of the hose-reel 2 and provided with a grooved guide wheel or sheave 44, adapted to receive and guide the hose onto the reel. 45 is an endless chain connected to said carriage and passing over carrying-pulleys 46 at the respective sides of the truck-frame 1. 47 is a longitudinal counter-shaft carrying at one end a pinion 48, adapted to have operative engagement with a side flange or head of the reel 2, and at its other end a pinion 49, which meshes with and drives a gear-wheel 50, carried by a crank-shaft 51, as shown in Fig. 10. 52 is a crank-shaft arranged at the opposite side of the truck-frame to that at which the crank-shaft 51 is arranged and operatively connected thereto by the connecting-rod or pitman 53 engaging the respective cranks of the two shafts.

25 In the construction shown the crank-shaft 52 carries one of the chain-pulleys 46, while the other crank-shaft 51 is independent of the other chain-pulley at the same side of the truck-frame.

30 54 is a secondary crank on the crank-shaft 52 and adapted in connection with the mechanism hereinabove described to reverse the direction of the movement imparted by the crank-shaft 51 to the crank-shaft 52 at the will of the operator, as well as automatically, in a continued reeling or winding up of the hose upon the hose-reel.

35 55 is a rocking member arranged adjacent to the secondary crank 54 aforesaid and provided at its respective ends with hook-shaped ends 56, which are adapted to be alternately moved into the path of the crank 54 to engage said crank to hold the same from further movement in the direction in which it had previously traveled. With such holding of the crank 54 as described the other crank of the crank-shaft 51 will pass its "dead-center," and its further movement will impart motion to the secondary crank 54 and its 40 shaft 52 in a direction opposite to that in which the same had previously moved.

50 57 and 58 are spring-dogs engaging ratchet-teeth on the opposite sides of the rocking members 55 and adapted to hold the same fixedly in position when one or the other of said dogs is not moved out of active engagement with the ratchet-teeth of such rocking member.

55 59 is a rock-shaft extending longitudinally of the truck from the operator's station to adjacent relation to the aforesaid spring-dogs 57 and 58 and provided with a rocking head or cross-arm 60, the respective ends of which are adapted to alternately engage against said spring-dogs to move the same away from their engagement with the rocking members 55 at the will of the operator.

The rocking member is mounted centrally on an operating-shaft 61, which extends to a position adjacent to the operator, so as to enable him to effect the "reversing" operation by hand when circumstances so require or as his judgment may suggest.

In the present construction as shown in the drawings the described reversing operation is also effected in an automatic manner by the following-described mechanisms: 62 is a bell-crank lever, one end of which has operative engagement with one of the spring-dogs aforesaid, while its other end is arranged in the path of the traversing carriage 43 and adapted to be operated by the same as such carriage nears one end of the main reel. By this means the rocking member 55 is released from such dog, so that a further movement of the carriage 43 will by direct engagement with one end of said rocking member move or rock the same, so that the hook 56 at the opposite end of the rocking member will be moved into the path of the secondary crank 54, in the manner hereinbefore described, to cause a reversal in the direction of the movement of such traversing carriage. 63 is an arm carried by a shaft or rod 64 and adapted to have operative engagement with the other of the spring-dogs aforesaid in manner similar to the bell-crank lever 62. The shaft 64 extends transversely across the main truck 1 and at its end is connected to one end of a lever 65, the other end of which is arranged in the path of the traversing carriage 43 and is adapted to be operated by the same as said carriage nears the end of its movement in a direction toward said lever. By such means the rocking member 55 is released from the last-mentioned spring-dog, and a further movement of the carriage 43 will through the shaft 64 impart a rocking movement to said member 55, so that the other hook 56 will be moved into the path of the secondary crank 54 to effect in the manner hereinbefore described a reversal in the direction of the movement of such traversing carriage.

Having thus fully described my said invention, what I claim as new, and desire to secure by Letters Patent, is—

1. In a hydraulic street-cleaning apparatus of the character herein described, the combination of a portable truck, a hose-reel mounted thereon and provided with a hollow axle forming a water-conduit, a delivery-hose connected to an end of said axle, a lead of hose connected at one end to said axle and adapted to reel thereon, an auxiliary pumping-engine arranged stationary with relation to the portable truck aforesaid, a motive-fluid throttle-valve for said engine, means for connecting the lead of hose aforesaid to the water-education of said engine, and means extending from the portable truck to the auxiliary engine for controlling the throttle-valve of the same, substantially as set forth.

2. In a hydraulic street-cleaning apparatus of the character herein described, the combination

nation of a portable truck, a hose-reel mounted thereon and provided with a hollow axle forming a water-conduit, a delivery-hose connected to an end of said axle, a lead of hose connected at one end to said axle and adapted to reel thereon, and closure means for the respective ends of said lead of hose adapted to maintain a water-filled condition of the same during the reeling operation, substantially as set forth.

3. In a hydraulic street-cleaning apparatus of the character herein described, the combination of a portable truck, a hose-reel mounted thereon and provided with a hollow axle forming a water-conduit, water-delivery hose

connected to the respective ends of said axle, a lead of hose connected at one end to said axle and adapted to reel thereon, and closure means for the respective ends of the delivery-hose and the lead of hose adapted to maintain a water-filled condition of the lead of hose during the reeling operation, substantially as set forth. 20

Signed at Chicago, Illinois, this 8th day of May, 1902.

PETER SHANNON.
